 Filed May 15, 1961, Ser. No. 119,765
 8 Claims. (Cl. 310—27)

This invention relates to a lineal motion transducer and is particularly concerned with an electro-mechanical transducer for vibratory testing, and the like, it being a general object of this invention to provide an electro-mechanical structure wherein moving mass is reduced to a minimum and wherein a high degree of mechanical and electrical efficiency is attained.

Machines of the type under consideration have had certain limitations of design which has resulted in restricted use. Mainly, the armatures of such machines have been heavy and bulky with the result that the overall construction has been inefficient. Since the armature is a reciprocating element, its weight is an important factor requiring power for its operation or reciprocation. That is, the heavier the armature, the less capacity it will have to carry a component to be tested. It is, therefore, a primary object of this invention to provide a light weight armature in a machine of the type under consideration so that the carrying power of the machine is increased to a maximum degree. Such a construction also results in a lower power consumption and in more accurate response to line signals.

Heretofore, electro-mechanical transducers have been characterized by circular armature coils and by external and internal field poles with magnetic flux extending across an annular air gap occupied by the said armature coil. More recently, however, radical departure from the circular configuration has been suggested and tried with a degree of success but great sacrifices in the electrical efficiency. For example, X-shaped armatures have been resorted to wherein the structural X per se forms the armature conductors, and in such a machine extremely high amperage must be employed accompanied by high losses, etc. In theory, it is the large cross-section of the armature conductors in such an arrangement that requires the high current requirements. On the contrary, the present invention employs relatively low current and relatively small cross-sectioned armature conductors accompanied by low losses. The present invention retains the long proven concept of a multi-turn armature coil, attaching said coil to a useful load by means of a minimum of structure. The useful load in the case under consideration is a component (not shown) to be reciprocated, the armature being formed into or onto a light weight carriage that is attached to the said useful load.

It is an object of this invention to provide a versatile lineal transducer having a rectilinear or reciprocating motion and with a minimum of built-in mass inertia. With the structure that I provide the armature structure is no more than a single flat web with a rail for facilitating attachment to the load.

It is another object of this invention to provide a configuration and combination of parts and elements wherein the coils, both field and armature coils, can be preformed and simply installed in the structure upon assembly and/or for replacement.

The various objects and features of this invention will be fully understood from the following detailed description of the typical preferred form and application thereof, throughout which description reference is made to the accompanying drawings, in which:

FIG. 1 is a section view taken through the transducer in perspective.

FIG. 2 is an enlarged detailed section of a portion of the structure shown in FIG. 1.

FIG. 3 is a fragmentary perspective view of one convolution or coil of the armature winding that I provide.

FIG. 4 is a plan view of the field-frame that characterizes the transducer shown in FIG. 1.

The lineal transducer or shaker of the present invention is driven electrically and operates on alternating current. The frequency and power of the current is varied as circumstances require in order to gain the desired frequency and intensity of vibration, and for this purpose, any suitable electronic power supply may be provided. It will be readily understood that the frequency of vibration in the machine will follow the frequency of the alternating current and that the intensity or stroke of the vibration in the machine will follow the power input or voltage and amperage which is supplied. Further, it will be apparent that impacts can be created by applying a single pulse of D.C. electricity, or long stroke acceleration can be created in a like manner.

The shaker that I illustrate in the drawings is a unit of construction adapted to carry and vibrate a load such as a unit of machinery or of electronic equipment that requires observation under predetermined vibratory conditions. As shown, the unit of construction comprising the present invention involves, generally, a field-frame F and an armature-carriage A. The field-frame F is the stationary element, whereas the armature-carriage A is the moving element.

The field-frame F is a rigid structure adapted to be fixedly positioned, or of substantial weight so that its inertia has considerable effect. The field-frame F can be made to have a simple pair of magnetic poles, N and S, or it can be multi-poled having as many pairs of poles as circumstances may require. In the drawings I have shown three pairs of poles, N and S, and with three armature windings W each operating between opposing field poles. It will be apparent that the present invention in its broad sense contemplates the combination of a single armature winding W and a single pair of field poles N and S, and that the direction of reciprocatory movement is in opposite directions longitudinally of the field pole structure as is indicated by the arrow a.

The field-frame F involves, at least, a pair of elongate magnets 10 and 20 having opposed pole faces 11 and 21, respectively. The faces 11 and 21 are spaced to accommodate the intervening armature-carriage parts later described, and said faces are of limited transverse extent, or width. As shown, the faces 11 and 21 are straight and parallel and of uniform width. The magnets 10 and 20 are alike, being formed as rigid bars anchored at one or both ends. In the preferred arrangement, the magnets 10 and 20 are electromagnets comprising a solid body of, or laminated, electrical steel anchored at opposite ends to rails 12 and 13 and with a field winding 14 to create the necessary magnetic flux to cross between the faces 11 and 21. Further, when multiple pairs of magnets are employed the intermediate magnets 10 and 20 are combined in one solid body, or lamination, each having oppositely disposed faces 11 and 21. Thus, it will be apparent that as many pairs of magnets can be employed as is desired.

The armature-carriage A is a rigid structure adapted to be reciprocably moved relative to the field-frame F, and it is of minimum weight and inertia. The armature-carriage A is essentially little more than the winding W of which it is mainly composed, said winding W being attached together in a common body 30 that is essentially the carriage to which the work load is attached. More specifically, portions of the multi-coiled conductor 31 of the winding W are cast or molded in the body 30 to extend through the air gap at a right angle to the

longitudinal axes of the magnets 10 and 20 (not the polar axes). In accordance with the invention, the body 30 is dielectric and is co-extensive with the pole face 11, the conductor 31 being imbedded therein so that adjacent coil portions are insulated from each other. As shown, there is a single layer of conductor 31 to be reciprocated between the pole faces 11 and 21, and the body 30 is but slightly greater in thickness than the cross-section of a single conductor, and said conductors are spaced slightly to extend one adjacent the other.

In carrying out the preferred form of this invention, the winding W is also attached together in a common body 40 that is fixed to the field-frame F. More specifically, portions of the multi-coiled conductor 31 of the winding W are cast or molded in the body 40 to extend transversely through the air gap at a right angle to the longitudinal axes of the magnets 10 and 20 (not the polar axes). In accordance with the invention, the body 40 is dielectric and is co-extensive with the pole face 11 or 21, as the case may be, the conductor portions 31 being imbedded therein so that adjacent coil portions are insulated from each other. As shown, there is a single layer of conductor portions 31 to be superimposed upon the face 11 or 21, in which case the body 40 is slightly greater in thickness than the cross-section of a single conductor and such conductors are spaced slightly to extend one adjacent the other.

The winding W can be a single coil comprising one or more conductors 31 and in the preferred form of the invention, the said conductor 31, or conductors, is of the multi-strand type in order to have considerable flexibility. As shown, each coil of the conductor 31 has a pair of opposite loops 33 and 34 that extend freely intermediate the bodies 30 and 40, and these loops 33 and 34 permit freedom for the body 30 to move independently of the fixed body 40.

The bodies 30 and 40 are cast or molded so as to encase the portions of the winding W, as above described, and said bodies are secured in place with the body or bodies 30 movable, and the body or bodies 40 fixed to the pole faces 11 and 21. The manner of securing can be varied, it being preferred to bond the bodies 40 to the faces 11 and 21 by means of a cement or adhesive. Further, since there are opposed pole faces 11 and 21 there are actually two windings W which are combined as one, or preferably secured together by joining the two bodies 30 that are involved. The two bodies 30 are either cast or molded integrally as one, or they are bonded together by means of a cement or adhesive.

As stated, the armature-carriage A is provided to move a useful load to which it must be attached. Therefore, I prefer to secure the movable bodies 30 to a carriage 50 to have supporting and driving engagement with a load. In practice, the carriage 50 comprises a web 51, preferably of metal such as aluminum, that extends in a plane intermediate the faces 11 and 21 and between the two bodies 30. The said bodies 30 carrying the armature conductor 31 are then cast or molded onto or bonded to the web 51. The web can be relatively thin and it supports a rail 52 with fastener openings 53 for mounting engagement with the load. In practice, when a multi-magnet unit is constructed as shown, a mounting plate 55 joins the rails 52 properly spacing them, one parallel with the other.

In the preferred form of the invention illustrated and hereinabove described the armature winding involves portions that are stationary and portions that move. Broadly, these armature windings can be varied in physical formation as circumstances require. For example, the moving portions of the windings can be formed of laminations that form the body of the armature-carriage, in which case flexible loops extend freely to a stationary portion or portions as above described. Also, for example, induction can be utilized in the armature windings, in which case the entire winding can move with the armature car-

riage, thus avoiding the use of flexible loops and stationary winding portions. With this latter induction concept of winding the armature, unlimited travel can be gained by operating the armature between a long series of field elements.

From the foregoing, it will be apparent that I have provided a relatively simple field and armature construction that can be readily manufactured of easily formed and easily assembled parts. The armature-carriage element A that is shown is made somewhat shorter in longitudinal extent than the field-frame element F in order to permit the desired longitudinal reciprocatory movement. The armature-carriage can be supported in various ways and, for example, it can be carried by an anti-friction fluid support, in which case the frame provides a closed chamber 55 supplied with fluid under pressure through fluid galleries 56. The said galleries discharge fluid in a manner to flat the armature-carriage in proper working position. Further, the fluid that is introduced for support of the carriage is also effective in heat transfer from the unit as it is operating.

Having described only a typical preferred form and application of my invention, I do not wish to be limited or restricted to the specific details herein set forth, but wish to reserve to myself any modifications or variations that may appear to those skilled in the art and fall within the scope of the following claims.

Having described my invention, I claim:

1. An electro-mechanical transducer including, a field magnet comprising spaced pole faces, an armature comprising a winding having a fixed portion and a reciprocable portion, said two portions being joined by flexible loop portions, the fixed portion of the winding being positioned between the pole faces, and the reciprocable portion of the winding being secured to a body for free reciprocatory movement.

2. An electro-mechanical transducer including, a field magnet comprising spaced pole faces, an armature comprising a winding having a fixed portion and a reciprocable portion, said two portions being joined by flexible loop portions, the fixed portion of the winding being fixed to at least one of the pole faces, and the reciprocable portion of the winding being secured to a body for free reciprocatory movement.

3. An electro-mechanical transducer including, a field magnet comprising spaced pole faces, an armature comprising a winding having a fixed portion and a reciprocable portion, said two portions being joined by flexible loop portions, the fixed portion of the winding being fixed to at least one of the pole faces, and the reciprocable portion of the winding being encased in a body for free reciprocatory movement.

4. An electro-mechanical transducer including, a field magnet comprising spaced pole faces, an armature comprising windings having a pair of fixed portions and a reciprocable portion, said fixed and reciprocable portions being joined by flexible loop portions, the fixed portions of the windings being fixed to the pole faces, and the reciprocable portions of the windings being secured to a body for free reciprocatory movement.

5. An electro-mechanical transducer including, a field magnet comprising spaced pole faces, an armature comprising windings having a pair of fixed portions and a reciprocable portion, said fixed and reciprocable portions being joined by flexible loop portions, the fixed portions of the windings being encased in bodies that are fixed to the pole faces, and the reciprocable portions of the windings being secured to a body for free reciprocatory movement.

6. An electro-mechanical transducer including, a field magnet comprising spaced pole faces, an armature comprising windings having a pair of fixed portions and a reciprocable portion, said fixed and reciprocable portions being joined by flexible loop portions, the fixed portions of the windings being fixed to the pole faces, and the

reciprocable portions of the windings being encased in a body for free reciprocatory movement.

7. An electro-mechanical transducer including, a field magnet comprising spaced pole faces, an armature comprising windings having a pair of fixed portions and a reciprocable portion, said fixed and reciprocable portions being joined by flexible loop portions, the fixed portions of the windings being encased in bodies that are positioned between the pole faces, and the reciprocable portions of the windings being encased in a body for free reciprocatory movement.

8. An electro-mechanical transducer including, a field magnet comprising spaced pole faces, an armature comprising windings having a pair of fixed portions and a reciprocable portion, said fixed and reciprocable portions

15

being joined by flexible loop portions, the fixed portions of the windings being encased in bodies that are fixed to the pole faces, and the reciprocable portions of the windings being encased in a body for free reciprocatory movement.
